DRAWING MECHANISM FOR SPINNING FRAMES AND THE LIKE

Ban Lem Louie, Shanghai, China

Application November 4, 1938, Serial No. 238,902
In Great Britain February 17, 1938

3 Claims. (Cl. 19—131)

This invention relates to apparatus for drafting cotton slivers or rovings for the production of spun yarns, the apparatus being of the type wherein a sliver or roving is drafted between a pair of endless bands arranged around the middle pair of rollers of the spinning frame.

One object of the invention is to provide an improved apparatus of the above type in which a yielding pressure is applied to the slivers or rovings as they pass between the endless bands, similar to that obtained by the fingers in hand spinning and whereby a more even and stronger yarn is produced.

Another object of the invention is to provide an improved apparatus of the above type which is of simple construction, and easily assembled or dismantled in the minimum amount of time. The invention consists in an apparatus for drafting cotton slivers or rovings for the production of spun yarns of the type above referred to in which the upper and lower endless bands arranged around the middle pair of drawing rollers are provided at their forward ends, at a point between the middle and front pairs of rollers, with a pair of tensors which are slidably mounted within recesses formed in the cap bars, the upper tensor being resiliently mounted so as to be capable of movement towards and away from the lower tensor within the said slots, thereby to apply a yielding pressure to the slivers or rovings.

The invention also consists in the further features hereinafter described and claimed.

The invention will now be described with reference to the accompanying drawings in which: Figure 1 is a side elevation of the complete drawing mechanism constructed according to the invention.

Figure 2 a front elevation,
Figure 3 a plan,
Figure 4 a side elevation of the middle rollers and their associated endless bands,

Figure 5 a front elevation,
Figure 6 a plan, and
Figure 7 a side elevation of the upper tensor,
Figure 8 a front elevation of a modified form of upper tensor,
Figure 9 a front elevation of another modified form of upper tensor,
Figure 10 a front elevation, and
Figure 11 a plan of the bottom tensor.

In the drawings 1 is a stationary support on which is mounted three pairs of drawing rollers, namely, front rollers 2 and 5, middle rollers 3 and 6, and back rollers 4 and 7. The lower rollers

2, 3 and 4 of each pair, are rotatably mounted in the support 1, whilst the upper rollers 5, 6 and 7 which rest upon said lower rollers are held in their correct positions by cap bars, each of which comprises three blocks 8^a. The rear block is secured to an arm 8^b pivoted at 9 to the rearward portion of the support 1, whilst the middle and front blocks are adjustably mounted upon a rod 8^c secured at its rear end to the rear block 8^a. In this way each cap bar as constituted by 10 the three blocks 8^a can be swung upwardly out of its operative position. The blocks 8^a are provided with vertically disposed slots 10 extending the whole depth of the blocks and within which are slidably engaged the reduced ends 11 of the 15 upper rollers of each pair, said slots serving to position the rollers while permitting them to roll freely. The lower rollers are preferably fluted or grooved in well known manner.

The front blocks 8^a of the cap bars, at a point 20 between the front and middle pairs of rollers, are provided with additional slots or recesses 12. These slots or recesses 12 instead of extending the whole depth of the front blocks 8^a as is the case with the slots 10, stop short a little distance 25 from the underside of said blocks so as to be closed at their lower ends. Further, the recesses 12 instead of being arranged parallel to the slots 10 are disposed at a slight angle to the vertical for a purpose to be referred to later. 30

The slots 12 engage with the ends of a pair of upper and lower tensors 13 and 14 which extend between the cap bars parallel to the rollers. The bottom tensor 14 shown in detail in Figures 10 and 11 is in the form of a narrow flat bar the ends of which are slightly reduced in width for slidably engaging the slots 12 such reduced portions being made thicker than the rest of the bar so as to form a stepped up portion 15 which is slightly higher (about $\frac{1}{16}$ of an inch) 40 than the rest of the tensor. The stepped up or thickened end portions 15 of the bottom tensor serve not only to prevent the said tensor from inclining to one side or the other in the slots 12 but also normally constitute supports for the upper tensor 13. 45

The upper tensor 13 which is also reduced at its ends to engage the slots 12 is provided in the middle of its length with a pin 16 which projects vertically from the upper surface of said bar, whilst on each side of said pin, at a distance therefrom is provided recesses 17 and 17^a. These recesses which are open at the top extend downwardly to within a short distance of the bottom surface of the bar so as to leave rela- 50 55

tively narrow portions 18 and 18^a at these parts of the bar.

Secured to that side of the tensor 13 remote from the front pair of rollers 2, 5 and adjacent to the two ends of each of the slots 17 and 17^a are four prongs or guide pieces 19, 19^a and 20, 20^a which extend outwardly from said bar and downwardly for some distance below the same, the said prongs or guides being disposed along the length of the bar in two pairs, one pair to each slot.

The underside of the upper tensor 13 is flat and when placed in position with its reduced ends in the slots 12 of the cap bars, normally rests upon the raised end portions of the lower tensor 14 so as to leave a gap 21 between the upper and lower tensors extending substantially the whole length thereof.

Arranged around the upper middle roller 6 is a pair of endless bands 22 and 22^a which at their upper part extend forwards and downwards through the slots 17 and 17^a and thence round the front edges 18, 18^a of the upper tensor 13 which may be suitably rounded off, back through the gap 21 and two pairs of prongs or guides 19, 19^a and 20, 20^a to the roller 6 again. A second pair of bands 23 and 23^a are similarly arranged around the lower middle roller 3 the sand bands in this case passing upwardly from the roller 3, between the pairs of prongs 19, 19^a and 20, 20^a from whence they pass around the front edge of the lower tensor 14, which may be rounded off similarly to the upper tensor, after which they enter the gap 21 and pass back through the pairs of prongs 19, 19^a and 20, 20^a to the roller 3 again. The lower endless bands are revolved by means of the bottom middle roller 3 which is driven in any well known manner by suitable mechanism not shown, the upper bands being also revolved due to their frictional contact with the lower bands.

In order to press the upper rollers 5, 6 and 7 firmly against the lower rollers 2, 3 and 4 and thereby cause the upper and lower drawing elements of each pair to move at the same surface speed, a saddle mechanism is provided which comprises a front saddle 24 bearing at its forward end upon the reduced central portion of the upper front roller 5 and at its rear end resting upon a second or rear saddle 25 which at its ends bears upon the reduced central portions of the top middle and back rollers 6 and 7.

Pressure is obtained by means of a lever 26 which is pivotally connected at its upper end to the front saddle 24 and extends downwardly through a slot 27 in the rear saddle its lower end being slotted at 28 to receive one end of a lever 29 which passes through said slot and is hooked at 30 to a fixed part of the frame, the other end of the lever being weighted at 31.

Secured at its upper end to the underside of the front saddle 24, at a point opposite the pin 16 of the upper tensor 13, is a spring 32 which fits over the said pin so as to rest at its lower end upon the top of said upper tensor. In this way a resilient pressure is applied to the top tensor by the front saddle 24 through the spring 32 whereby the top pair of bands 22 and 22^a are yieldingly pressed against the lower pair of bands 23 and 23^a, such pressure of the bands being similar to that produced by the fingers in hand spinning.

The recesses 12, in which the top and bottom tensors are slidably mounted, are given a slight inclination from their upper to their lower ends

in a direction away from the plane passing through the axes of the middle rollers, so that a tensioning of the upper and lower pairs of endless bands 22, 22^a and 23, 23^a, takes place as the said tensors are pressed downwardly in their recesses under the pressure of the spring saddle mechanism. Should greater tensioning be required than that afforded by the inclination of the slots 12, then the front and/or middle blocks 3^a of the cap bars may be adjusted along their associated rods 8^c by means of set screws 8^d (Figure 3) until the required tensioning is obtained.

As the slivers or rovings 33 are drawn through the rollers between the upper and lower pairs of bands 22, 22^a and 23, 23^a the upper tensor 13 is free to adjust itself within the slots 12 against the action of the spring 32 whereby the depth of the gap 21 between the upper and lower tensors is varied and the upper bands 22, 22^a thereby caused to apply a yielding pressure to the slivers or rovings which pressure is closely akin to that produced by hand spinning and which results in the production of more even and stronger yarn. Also by the resilient mounting of the upper tensor 13 such adjustment of the upper pair of bands is possible without interfering with the normal pressure of the saddle mechanism upon the drawing rollers and through the spring upon the said tensor. Further, the side walls of the slots or recesses 17 and 17^a in the upper tensor constitute guides for the top stretch of the upper pair of bands 22, 22^a whilst the two pairs of prongs or guide pieces extending downwardly from said tensor serve to position the bottom stretch of the upper bands as well as both the top and bottom stretches of the lower pair of bands 23, 23^a.

Preferably the side walls of the recesses 17, 17^a in the upper tensor 13 are formed at their upper ends with inwardly projecting pins 34 which extend over the side edges of the top stretch of the upper pair of bands 22, 22^a thereby by ensuring the retention of said bands within their respective recesses.

If desired the pins 34 may be dispensed with according to the modified form of upper tensor illustrated in Figure 8 in which case only the side walls of the recesses serve to guide the top stretches of said bands, whilst in a further modified form of upper tensor as illustrated in Figure 9, the prongs or guide pieces may be omitted.

Clearers 35, 36 and 37 are provided for the top front and middle rollers, the top rear roller and the bottom front roller respectively.

The general arrangement is extremely simple and can be easily dismantled for examination or adjustment it only being necessary to remove the weight 31 from the lever 29 whereupon the whole of the saddle mechanism can be removed in one operation after which the top rear and front rollers can be slid upwardly out of the cap bars as well as the middle top roller together with the upper bands and upper tensor, thus leaving only the lower rollers in the support 1.

It will be understood that whilst the invention has been described with reference to one set of twin front, middle and rear pairs of drawing rollers, any number of such sets may be provided alongside one another according to the overall length of rollers and drawing frame required.

I claim:

1. An apparatus for drafting cotton slivers for the production of spun yarns, comprising in combination, front, middle and back pairs of upper and lower drawing rollers, a stationary support in which the lower roller of each of the said

pairs is rotatably mounted, cap bars pivotally connected at one end to the said support and having slots within which are slidably engaged the reduced ends of the upper rollers of each 5 pair, said slots serving to position said upper rollers whilst permitting them to roll freely upon the lower rollers, saddle mechanism mounted upon said support for applying pressure to said drawing rollers, additional recesses in the said 10 cap bars at a point between the middle and back rollers, a pair of upper and lower tensors mounted on top of one another and slidably engaging at their ends within the said recesses, a pair of endless bands arranged around the middle pair 15 of drawing rollers and the said pair of tensors, and spring means interposed between said upper tensor and the saddle mechanism whereby the upper tensor is capable of limited movement towards and away from the lower tensor within 20 said recesses to apply a yielding pressure to the slivers passing between the bands.

2. An apparatus for drafting cotton slivers for the production of spun yarns, comprising in combination, front, middle and back pairs of 25 upper and lower drawing rollers, a stationary support in which the lower roller of each of the said pairs is rotatably mounted, cap bars pivotally connected at one end to the said support and having slots within which are slidably en- 30 gaged the reduced ends of the upper rollers of each pair, said slots serving to position said upper rollers whilst permitting them to roll freely upon the lower rollers, saddle mechanism mounted upon said support for applying pressure to said drawing rollers, additional recesses in the said cap bars at a point between the middle and back rollers, a lower tensor in the form of a bar having stepped-up ends and slidably engaging at its 35 ends within the said recesses, an upper tensor 40 also slidably mounted at its ends in said recesses and normally resting on the stepped-up ends of the lower tensor so as to leave a gap between the said tensors extending sub- 45 substantially the whole length thereof, pairs of endless bands arranged around the middle pair of drawing rollers and the said pair of tensors, the adjacent upper and lower stretches of said bands passing through the gap between said tensors, recesses in the upper tensor for positioning the top stretches of the upper bands and prongs depending from said upper tensor for positioning the bottom stretches of the upper bands and both top and bottom stretches of the lower bands, a spring mounted at its lower end upon a pin fixed to the top side of the upper tensor and at its upper end bearing against the underside of the saddle mechanism whereby the upper tensor is capable of limited movement towards and away from said tensor within said recesses to apply a yielding pressure to the slivers 50 passing between the bands.

posed between said upper tensor and the saddle mechanism whereby the upper tensor is capable of limited movement towards and away from the lower tensor within said recesses to apply a yielding pressure to the slivers passing between the bands. 5

3. An apparatus for drafting cotton slivers for the production of spun yarns, comprising in combination, front, middle and back pairs of upper and lower drawing rollers, a stationary support 10 in which the lower roller of each of the said pairs is rotatably mounted, cap bars pivotally connected at one end to the said support and having slots within which are slidably engaged the reduced ends of the upper rollers of each 15 pair, said slots serving to position said upper rollers whilst permitting them to roll freely upon the lower rollers, saddle mechanism mounted upon said support for applying pressure to said drawing rollers, additional recesses in the said 20 cap bars at a point between the middle and back rollers, which recesses are slightly inclined outwardly away from the middle pair of rollers from top to bottom, a lower tensor in the form of a bar having stepped-up ends and slidably 25 engaging at its ends within the said recesses, an upper tensor also slidably mounted at its ends in said recesses and normally resting on the stepped-up ends of the lower tensor so as to leave 30 a gap between the said tensors extending substantially the whole length thereof, pairs of 35 endless bands arranged around the middle pair of drawing rollers and the said pair of tensors, the adjacent upper and lower stretches of said bands passing through the gap between said 40 tensors, recesses in the upper tensor for positioning the top stretches of the upper bands and prongs depending from said upper tensor for positioning the bottom stretches of the upper bands and both top and bottom stretches of the lower bands, a spring mounted at its lower 45 end upon a pin fixed to the top side of the upper tensor and at its upper end bearing against the underside of the saddle mechanism whereby the upper tensor is capable of limited movement towards and away from said tensor within said recesses to apply a yielding pressure to the slivers passing between the bands. 50
